UNITED STATES PATENT OFFICE.

JOHN JASUS, OF CATLIN, ILLINOIS.

DESIGN FOR A NAIL.

58,442.

Specification for Design.

Patented July 19, 1921.

Application filed April 28, 1921. Serial No. 465,917. Term of patent 7 years.

To all whom it may concern:

Be it known that I, JOHN JASUS, a citizen of Czecho-Slovakia, residing at Catlin, in the county of Vermilion and State of Illinois, have invented a new, original, and ornamental Design for a Nail, of which the following is a specification, reference being had to the accompanying drawing, forming part thereof.

The figure is a view in perspective of a nail, showing my new design.

I claim:

The ornamental design for a nail, as shown.

JOHN JASUS.
